Application May 4, 1943, Serial No. 485,585

12 Claims. (Cl. 33—49)

1

This invention relates to the field of gunnery and particularly to the control of the movement of a sighting device such as a telescope while tracking a target and of its angular position relative to a gun.

Ideally, automatic means move a sighting device, herein termed a sight, at a proper rate to compensate for the relative movement of a target and thus to maintain the target in the field of view of the sight, and at the same time supplemental means determine and introduce the sight deflection angle, that is, the lead angle of the gun relative to the sight which is a function both of the range and of the rate of movement of the sight.

The invention is herein disclosed as applied to the control of the position of the sight in azimuth and of its training rate. In such application a power device drives a training table on which the sight is mounted relative to a fixed circular rack, and the effective rate is to be regulated so as to comport with the rate of relative movement of the target. The purpose of the invention is to provide mechanism of a type that will enable the operator accurately, smoothly and simply to introduce corrections as errors develop.

It is a characteristic of the invention that the operator directly and temporarily effects an acceleration of the sight to correct for an accumulated error, and that this acceleration is converted to a modification of the effective rate of the power device. As preferably embodied the invention contemplates a variable speed device the output of which effects the movement of the sight at a rate which is the final result of accelerations introduced by the operator. Considering the bearing of a sight, although it will be apparent that the invention is equally applicable to the control of a sight in elevation, the rate at which the bearing is automatically generated is suitably represented by the output of a variable speed device the rate member of which is under the direct control of another variable speed device the rate member of which is adjusted by the operator. Thus the quantity introduced by the operator produces a change of rate of the first variable speed device an amount depending upon the value and duration of the quantity, and the output of the first variable speed device is accelerated.

To effect a correction in the position of a sight in addition to correcting the rate of movement, the invention also contemplates introducing the change of rate of the first variable speed device directly into its output. Also it is contemplated that the movement representing the quantity in-

2

roduced by the operator may be introduced directly into the generated movement in order to give an immediate indication of the fact and direction of a correction, thus enabling the operator to check on an action in anticipation of the modified output of the generating mechanism the appearance of which after the operator introduces a movement representative of acceleration involves an appreciable period of time.

10 While theoretically the source of power which drives the power elements of the variable speed devices may drive the sight, in practice it is desirable to employ an additional servo motor for this purpose. In such case the relay for controlling the servo motor is differentially controlled by the output of the position generating mechanism and by the position of the sight. In other words the output of the differential represents the error or disagreement between the generated position and the response of the servo motor.

15 This relay may be of the so-called pneumatic type in which the control member of the servo motor is spring biased to central or neutral position and is operatively connected to a pneumatically controlled movable member, such as a diaphragm or a piston, that has normally balanced air pressure on both sides but the balance of which is under the control of a valve member that is connected to be actuated by the output of the differential. Also there may be provided a suitable pneumatic impulse mechanism through which the movement directly caused by the operator acts upon the control member of the servo motor and anticipates the arrival of the effect of the movement through the generating mechanism.

20 In case the mechanism is to be used for training control on board ship it is desirable to maintain a constant indication of a fixed meridian or other azimuth datum. It is contemplated that for this purpose an azimuth gyroscope may be used so mounted as to effect a differential action in control of the servo motor relay.

25 The invention also contemplates means for utilizing the rate of generated movement to determine and introduce the sight deflection angle, means to control the acceleration of the servo motor, and other features which will more fully appear from the following description of the illustrated embodiments of the invention.

30 Referring now to the drawings, Fig. 1 is a diagram representing one simple embodiment of the invention.

35 Fig. 2 is a similar diagram of a modified embodiment of the invention.

3

Fig. 3 is a similar diagram of another modified embodiment of the invention.

Fig. 4 is a sectional detail of the part of the pneumatic control system that is carried on the base with the gyroscope in the construction of Fig. 3.

Fig. 5 is an enlarged sectional detail of one of the chamber members of the impulse means.

Fig. 6 is a diagrammatic representation of the problem to which the mechanism of Fig. 3 is suited.

Fig. 7 is a diagram representing a modified form of connection between the impulse means and the motor control.

Fig. 8 is a section on line 8-8 of Fig. 7.

Fig. 9 is a view similar to Fig. 8 with some of the parts displaced.

In the design of apparatus shown in the drawings a sight 1 is mounted on elevation trunnions bearing in uprights or legs 2 fixed on a training table or mount 3 mounted for rotation inside a fixed, circular, peripheral rack 4. A hand controller 5 which has a handle on one end and a gear segment on the other, is pivoted on a cross plate connecting the legs 2 on an axis perpendicular to the training mount. Its toothed end meshes with a rack 6 which has on one end a ball carriage of a variable speed drive 7.

Adjacent the variable speed drive 7 is a second variable speed drive 8. These variable speed drives are of the two ball integrator type consisting of a power driven disc 7a and 8a, respectively, a rate member 7b and 8b, respectively, which is a ball carriage and two balls therein, and an output roller 7c and 8c, respectively. A constant speed motor 9 is geared to drive the discs 7a and 8a.

This drive mechanism is operative to drive an output shaft 10 that functions as a primary movable member to produce or control the angular movement of the mount 3 and hence to train the sight 1. The output roller 7c is geared to shaft 11 which has a pinion 12 engaging rack 13 that carries ball carriage 8b. Shaft 10 is mechanically operated by the output roller 8c.

Taking a second as the unit of time and a radian as the unit of angular motion of the shaft 10, it is evident that the position of the rate member of the variable speed drive 8 represents radians per second, and that the position of the rate member of the variable speed drive 7 represents rate of change of rate, that is, radians per second per second. In other words the first represents velocity or rate of change of position and the second represents acceleration or rate of change of velocity. Therefore when the operator moves the controller 5 he changes the rate of acceleration and the resulting acceleration is integrated through the period of time that the operator holds the handle off-set so that the movement of the output roller 7c represents change of rate of change of position; and the product of the rate represented by the position of the member 8b multiplied by time represented by the rotation of disc 8a is change of angular position of shaft 10. Therefore it will be seen that a movement of the controller 5 modifies the rate of the shaft 10, and a much smoother and more exact control of the movement of the shaft 10 is thus obtained than is possible by applying the movement introduced by the operator directly to the rate member 8b.

As above stated the movement of the shaft 10 effects the training of the mount, and since it is the accumulation of an error which apprises the operator that a change in rate is needed, it is

4

desirable to remove the accumulated error coincident with the effecting of the change of rate without requiring an overcorrection of the rate. To bring this about the movement of the output roller 7c is added to that of the output roller 8c, and the shaft 10 is thus set ahead or back depending upon the direction of movement of the controller 5. As shown, the shaft 11 is geared to a shaft 14 that is geared to one of the inputs of a differential 15, the output roller 8c being connected to the other input, while the output of the differential drives shaft 10. Thus the change of rate of change of position is introduced directly into the differential 15 to effect a change of position of the shaft 10.

Since the complete effect of movement of the acceleration roller 7c is not instantaneous upon the movement of the rack 6 through the controller 5, it is desirable for the purpose of checking 20 to have the rack 6 act directly upon the shaft 10 so as to give an immediate indication to the observer through the telescope that the controller has been moved and the direction of the ensuing 25 correction. To accomplish this it is suitable to introduce the movement of the rack 6 directly into the position of the shaft 10. This may be done by a second differential 16 to one input of which the rack 6 is connected by shaft 17, while the output of differential 15 is connected to the 30 other input and the shaft 10 is connected to the output.

In the form shown in Fig. 1 the shaft 10 is connected directly to drive the mount 3. This assumes sufficient power in the motor 9 for the 35 purpose. As shown a training pinion 18 meshes with rack 4 and is carried on the end of a shaft bearing in a bracket 19 and having on its upper end a gear 20 that is driven from the shaft 10. Specifically a counter shaft 21 which is geared to 40 shaft 10 is operatively geared to drive gear 20 through shaft 22 and drive pinion 23.

The position of shaft 10 and hence the bearing of the sight 1 is transmitted through a shaft 24 that is geared to shaft 21 to a transmitter 25 45 of a synchronous electric transmission system which in turn transmits it to a gun (not shown). Means are also provided to determine and add to the transmitted value the sight deflection angle, that is, the angle between the sight and the gun. 50 This angle is the product of the rate of change of bearing and range or time of flight of a projectile which is a function of range.

As shown a multiplier 26 is provided, one input 55 member of which is set by the shaft 11 through pinion 27 and rack 28 so that it agrees with the setting of the ball carriage 8b and hence represents rate of change of bearing, and the other input member of which is set by handle 29 to introduce time of flight which simultaneously is shown on dial 30 that may alternatively be graduated in corresponding values of range. The output of the multiplier 26 actuates shaft 31. The movements of shafts 24 and 31 are combined in differential 32 the output of 60 which is connected to drive the rotor of transmitter 25.

More commonly a servo motor suitably controlled by a relay mechanism will be needed to drive the mount 3, and such an arrangement is shown in Figs. 2 and 3.

Turning first to Fig. 2, an electric motor 33 is employed as the servo motor, the operating circuit of which is controlled by contact member 34 the position of which is differentially under 70 control of shaft 10 and the movement produced

40

2,405,047

5

by motor 33. It will be understood that the electric motor is selected only for the purpose of illustration and that electrically controlled clutches or another type of motor, such as a hydraulic motor may be employed, in which case the contact member would be of a form to control the flow of hydraulic fluid or to operate a swash-plate or other suitable form. Therefore the term "contact member" as used herein is not intended to be limiting but to include any member in direct control of the speed and direction of the motor.

As shown the member 34 is a pivoted electric contact that cooperates with two fixed contacts 35 which are reversely connected to the field of the motor, the common lead of the motor being connected to the contact 34 through a current source. The motor armature is connected through reducing gears to shaft 22' which carries gear 23 that drives the training pinion 18 as in the construction previously described. Shaft 22' is geared to shaft 21' that is geared to shaft 24', which latter shaft corresponds to shaft 24 in the construction of Fig. 1 and is differentially connected with the output of the sight deflection angle multiplier to drive the transmitter 25.

We now turn to the means for determining the position of the contact member 34. Centralizing springs bias the member to central or open circuit position and pneumatic means under the differential control of shafts 10 and 24' actuate the member selectively to one or the other contact position. The shafts 10 and 24' therefore may be considered as the primary movable member and the driven member respectively of a follow-up system.

As shown a piston 36 slidable in a cylinder 37 is pivotally connected to the free end of the pivoted contact member 34 and is normally centralized therein by springs 38. Air under pressure is admitted by pipe 39 to a chamber 40 adjacent to cylinder 37 that communicates through vents with the interior of the cylinder on opposite sides of the piston 36. The size of the vents is controlled by adjustable needle valves so that the flow can be regulated. A pipe 41 leads from the interior of the cylinder on each side of the piston to a valve block 42 in which is a piston valve 43 arranged in control of the valve ports of the two pipes 41. When the piston valve 43 is in central position as shown, the two ports of pipes 41 are equally uncovered and the flow in the two pipes is equal and hence the pressure on the two sides of piston 36 is equal. As the valve 43 moves up or down it more or less covers one of the ports and builds up a pressure on that side of the piston 36 and rocks the contact member 34 accordingly.

As above stated, this pneumatic means is under the differential control of shafts 10 and 24'. A differential 44 has one input connected to shaft 10 and its other input to shaft 45 geared to shaft 24', and its output is connected to a crank 46 pivoted to the connecting rod of piston 43.

Therefore a displacement of shaft 10 moves piston 43 in one direction or the other and so effects an unbalance of the air pressure on piston 36 and closes the contact in one direction of motor 33. The motor turns accordingly and trains the mount and the sight, at the same time tuning shaft 24' and shaft 45 and hence the center of differential 44 until the valve 43 is restored to central position and the motor stops.

The mechanism also includes a pneumatic impulse device operated by the controller 5 to give

6

a bias to the contact member 34 and close a contact and hence start or accelerate the motor 33 earlier than the action of the generating mechanism becomes effective on the contact member. 5 This is to compensate for the time lag and may be termed a front lash mechanism by analogy to the back lash that normally occurs in any mechanism. This impulse device consists of two closed cylinders having each a fixed partition 10 and a rotatable vane in it dividing the cylinders into two chambers and the corresponding sides of the two cylinders are connected. One vane is connected to be moved by the hand controller and the other is connected to give a bias 15 to the contact member.

As shown, a cylinder 47 has its vane geared to rack 6 and a cylinder 48 has its vane attached to the pivot arbor of member 34. The two sides are connected by pipes 49. The construction will be 20 better understood by reference to Fig. 5. It is apparent that instead of two pipes 49, there may be one pipe and the other side of each cylinder be open to atmosphere which would then be considered the second connecting means.

It will be clear that as the rack 6 is moved the vane of cylinder 47 will turn and create either an increase or decrease of pressure on one side, depending upon the direction of movement of the vane, and a reverse condition on the other side if a second pipe is used. The vane of cylinder 48 is biased accordingly and the contact member 34 is thus caused to close its contact in anticipation of the time that it would be closed by the operation of valve 43.

35 Means are provided to prevent a too rapid acceleration of motor 33. A viscous drag device 50 has one element fastened on the arbor of the contact member 34 and the other geared to one side of differential 51. The other side of the differential is loaded with an inertia member 52, while the center of the differential is geared to shaft 21'. The connection is such that as motor 33 is increasing its speed and the inertia member 52 is lagging behind, the drag member 50 is rotated in a direction to open the contact and so restrain the rate of acceleration. When the inertia member catches up so that the speed of its side of the differential corresponds to that of the center, then movement of the viscous drag 45 side of the differential stops and there is no tendency of the contact to open so long as the speed of the motor does not change. When the motor speed slows down, the inertia member keeps on going and produces a movement of the drag output 50 put in a direction to close the contact. In this way the motor is prevented from slowing down too fast.

The embodiment shown in Fig. 3 is the same as that of Fig. 2 except that a compass or equivalent gyroscopic means are provided to take care of a change of ship's course. In this case the gyroscope controls the pneumatic valve and in conjunction with its base it constitutes the differential to compare the generated and response 65 movements.

A gyroscope 53 is mounted in the usual gimbal mounting on a base 54, pivoted on the mount 3, so as to have three degrees of freedom and maintain its spin axis on a selected meridian. It 70 therefore functions as an azimuth gyro. Its frame 55 is pivoted on the base 54, preferably though not necessarily coaxially therewith. The valve block 42 is mounted on the base 54 and the connecting rod of the piston valve 43 is pivotally attached to a crank extension on the frame 75

55. The pipes 41 in this case lead to the valve block 42 by way of a special connection in the upper gyro pivot so as to allow relative angular movement. This is shown in detail in Fig. 4. The pipes 41 come in to a relatively stationary cap, the interior of which communicates with passages in the hub portion of the gyro support that connect with pipes 57 leading to the valve block.

In this case the shaft 10 has a worm on its end which meshes with a rack on the circular base 54, and turning of the shaft therefore rotates the base.

The operation will be understood from a reference to the diagram of Fig. 6. The ship on which the apparatus is mounted is assumed to be going in the direction OS. The gyro spin axis is pointing in the direction OM. It is assumed that the sight is pointed at a target in the direction OT. The ship's course relative to the datum meridian is Co and the relative bearing of the line of sight is Bs and the bearing relative to the datum meridian is B.

The apparatus under ideal condition operates at a rate which just keeps the sight on a target. Thus ball carriage 7b is at the center of disc 7a, the roller 7c is stationary, and the ball carriage 8b is off center just the right amount. But let it be assumed that the mount is training the sight to the right and that the rate is too slow and the sight lags behind the target until an error accumulates. Then it will be necessary to increase the training rate and immediately to advance the sight an amount to remove the accumulated error.

The operator will move his handle to the left so as to move the rack 6 to the right. The direction of the consequent movement of the parts is indicated by arrows. The rate member 7b, being moved off center to the right, will cause a movement of the roller 7c at a rate proportional to the displacement of the rate member and an amount depending upon the duration of the displacement. This moves the rate member 8b to the right and so steps up the rate of the roller 8c. A quantity proportional to the amount of movement of the roller 7c is added to the output of roller 8c at the differential 15. Also the differential 16 adds an instantaneous amount proportional to the movement of rack 6.

The effect of this relative angular movement of the shaft 10 is to turn the base 54 to the left or counter-clockwise relative to the mount 3. This causes movement of the valve 43 to the left relative to the valve block 42 and actuates the contact member 34 to engage the lower contact 35. This causes the motor 33 to run in a direction to turn the pinion 18 so as to make the mount 3 move to the right or clockwise. The mount carries the base 54 back relative to the gyro until the valve 43 regains its central position. Thereupon the motor stops.

Also the movement of the rack 6 through the pneumatic impulse devices 47 and 48 had closed the contacts 34, 35 earlier than the base 54 was moved to do it and in this way the corrective action of the motor was promptly started. The motor in accelerating turns the drag device 50 in the direction indicated by the arrow in Fig. 3, and this tends to open the contact 34 and hence prevents too rapid an acceleration of the motor. When the inertia element 52 gets up to speed corresponding with the input of the motor into differential 51, the drag member is stopped, but as the motor slows down the inertia member keeps on going and tends to close the contact 34

so as to keep the motor energized and thus prevent it from slowing down too rapidly.

Let it be assumed that the ship changes its course relative to the meridian OM but that the bearing angle B is unchanged. The relative bearing angle Bs has to be changed to compensate for the change in the angle Co. This is done automatically by the gyro. The turning of the ship turns mount 3 and hence base 54 relative to the gyro. The valve 43 is thus displaced, the balance of piston 36 is upset, member 34 is actuated and motor 33 caused to operate to bring the base to a position where valve 43 is again in the center. This keeps the sight on the target and changes angle Bs so as to keep angle B constant.

Now let it be assumed that angle B changes. The operator does the same thing as he would if the sight was lagging or getting ahead of the target. He moves the controller 5 in the proper direction to step up the shaft 10 and thus move the base 54 relative to the mount 3 with the result above described, the base being moved in the reverse direction to which the motor will move the mount.

Inasmuch as the movement of the controller 5 introduces acceleration by changing a rate that is integrated for a period of time in order to move the final rate member 8b, the resulting movement of the sight is smooth.

It will be appreciated that while for clarity of illustration the fixed contacts 35 are shown substantially spaced, in reality there is little clearance for the contact 34 and the movement of the pivot arbor is not substantial. Therefore when the vane of impulse device 48 is directly connected to the arbor of the contact member 34, as is the case in the construction of Figs. 2 and 3, the vane is limited to the restricted movement of the arbor when controller 5 is moved. The movement of the vane of impulse device 47 is proportional to the movement of the controller 5, and modifies the relative values of the pressures acting on the two sides of the vane of impulse device 48 to bias the contact member 34 one way or the other. With this construction there is a direct relation between the effective pressure acting on the impulse device 48 and the bias applied to the contact member 34, and the rate of leakage is proportional to a function of the pressure.

In Fig. 7 is shown a construction in which a variable relation between the bias applied to the contact member and the leakage which causes the removal of the bias is obtained. For this purpose a crank and spring connection between the device 48 and the contact member 34 as shown may be used. With this construction a crank arm 58 is secured to the pivot arbor of the contact member 34 and a crank arm 59 is secured to the shaft of the vane of the impulse device 48. The impulse device 48 is mounted so that its shaft is out of line with the pivot arbor of contact member 34, as shown in Figs. 7, 8 and 9. The outer ends of the crank arms 58 and 59 are connected by a spring 60.

With this construction movement of the controller 5 moves the vane of impulse device 47 as already explained, but instead of building up or modifying the pressure acting on the vane of impulse device 48 to bias the contact member directly, the pressure now moves the vane of the impulse device 48 and the arm 59 attached thereto, as illustrated in Fig. 9. The spring 60 as thus displaced imposes a force on the crank 58,

thereby placing a bias on the contact member 34. It will be seen that when the center of the cranks 58 and 59 are out of line as in Figs. 7, 8 and 9, the torque reaction from the spring 60 is less on arm 59 than on arm 58. The relation of these torques may be varied by changing the amount the centers are offset and it will be seen that the torque on arm 59 approaches zero as the displacement between the centers approaches the length of the effective radius of arm 58.

The operation with this construction is apparent. When the controller 5 is moved the vane of impulse device 47 is rotated and the vane and crank arm 59 of impulse device 48 are rotated a substantially equal amount. The spring 60 applies a bias to the contact member 34 through the crank arm 58 and modifies the energization of the motor 33. At the same time the action of spring 60 on the vane of device 48 is to return the arm 59 to be in angular agreement with the arm 58, as shown in Fig. 8, and thus eliminate the bias.

With this construction a much smaller difference in pressure on the two sides of the vanes of the impulse devices is necessary to apply a given bias to the contact member. Because of the smaller difference in pressure, the rate of leakage to permit the return to normal condition can be accurately controlled, the desideratum being that the bias produced by the spring 60 shall hold the contacts 34, 35 closed until the new speed of the motor is attained, whereupon the arm 59 should be in central position and the main control should have become effective to maintain that speed.

It will be apparent that the constructions described may be variously changed without departing from the principles involved. For example, the form of a variable speed device is immaterial so long as the displacement of the controller 5 determines the speed of output of the first device which in turn controls the speed of output of the second device.

I claim:

1. In gunnery, sight controlling mechanism comprising a rotatable mount, a sight on the mount, training means for the mount, a manual controller, two variable speed drives each including a rate control member and an output member, means operatively connecting the manual controller to the rate control member of one variable speed drive, means operatively connecting the output member of the said one variable speed drive to the rate control member of the other variable speed drive, means operatively connecting the output member of the said other variable speed drive to the said training means, multiplying mechanism having two input elements and one output element, means operatively connecting the rate control member of the said other variable speed drive to one input element of the multiplying mechanism, means for setting the other input element of the multiplying mechanism according to a function of range, whereby the output of the multiplying mechanism represents the sight deflection angle, and means for combining the movement of the output element of the multiplying mechanism with the movement of the training means to position a member in accordance with the gun train order.

2. In gunnery, sight controlling mechanism comprising a rotatable mount, a sight on the mount, training means for the mount, a manual

controller, two variable speed drives each including a rate control member and an output member, means operatively connecting the manual controller to the rate control member of one variable speed drive, means operatively connecting the output member of the said one variable speed drive to the rate control member of the other variable speed drive, a differential mechanism having two input elements and an output element, means operatively connecting the output member of the said other variable speed drive to one of the input elements of the differential mechanism, means operatively connecting the output member of the said one variable speed drive to the other input element of the differential mechanism, means differentially connecting the manual controller and the output element of the differential mechanism in operative relation to the said training means, multiplying mechanism having two input elements and one output element, means operatively connecting the rate control member of the said other variable speed drive to one input element of the multiplying mechanism, means for setting the other input element of the multiplying mechanism according to a function of range, whereby the output of the multiplying mechanism represents the sight deflection angle and means for combining the movement of the output element of the multiplying mechanism with the movement of the training means to position a member in accordance with the gun train order.

3. In gunnery, sight controlling mechanism comprising a rotatable mount, a sight on the mount, training means for the mount, a manual controller, two variable speed drives each including a rate control member and an output member, means operatively connecting the manual controller to the rate control member of one variable speed drive, means operatively connecting the output member of the said one variable speed drive to the rate control member of the other variable speed drive, a servo motor connected to operate the training means, a controller for the servo motor, means differentially connecting the training means, the manual controller and the output member of the said other variable speed drive to actuate the controller of the servo motor, and impulse transmitting means connected to be actuated by the manual controller and operative upon the controller of the servo motor to give an initial impulse to the controller for the servo motor upon movement of the manual controller.

4. In gunnery, sight controlling mechanism comprising a rotatable mount, a sight on the mount, training means for the mount, a manual controller, two variable speed drives each including a rate control member and an output member, means operatively connecting the manual controller to the rate control member of one variable speed drive, means operatively connecting the output member of the said one variable speed drive to the rate control member of the other variable speed drive, a reversible servo motor connected to operate the training means, a source of power for the motor, a contact member in control of the power connection, a base pivotally carried on the mount, a directional gyroscope having a frame pivotally mounted on the base and having a freedom of movement to maintain its spin axis fixed in space, means operatively connecting the output member of the said other variable speed drive to the said base, and means actuated by the relative movement of the

gyroscope frame and the base to operate the contact member.

5. In gunnery, sight controlling mechanism comprising a rotatable mount, a sight on the mount, training means for the mount, a manual controller, two variable speed drives each including a rate control member and an output member, means operatively connecting the manual controller to the rate control member of one variable speed drive, means operatively connecting the output member of the said one variable speed drive to the rate control member of the other variable speed drive, a reversible servo motor connected to operate the training means, a source of power for the motor, a contact member in control of the power connection, a base pivotally carried on the mount, a directional gyroscope having a frame pivotally mounted on the base and having a freedom of movement to maintain its spin axis fixed in space, a differential mechanism having two input elements and an output element, means operatively connecting the output member of the said other variable speed drive to one of the input elements of the differential mechanism, means operatively connecting the output member of the said one variable speed drive to the other input element of the differential mechanism, means differentially connecting the manual controller and the output element of the differential mechanism in operative relation to the base, and means actuated by the relative movement of the gyroscope frame and the base to operate the contact member.

6. In a follow-up system including a primary movable member, a servo motor and a driven member operated by the motor, a variable speed device for driving the primary movable member, a manual controller for regulating the speed of the variable speed device, a pneumatic control for the servo motor comprising a movable contact member controlling the application of power to the motor, a pneumatically movable member operatively attached to the contact member and normally constrained in central position, a source of pneumatic pressure, branch passages of substantially equal capacity leading the pneumatic pressure to the opposite sides of the pneumatically movable member, valve means for differentially venting the branch passages, differential means actuated by relative movement of the primary movable member and the driven member to position the valve means, and impulse means between the manual controller and the contact member operative to give an initial impulse to the contact member upon movement of the manual controller.

7. In a follow-up system including a primary movable member, a servo motor and a driven member operated by the motor, a variable speed device for driving the primary movable member, a manual controller for regulating the speed of the variable speed device, a pneumatic control for the servo motor comprising a movable contact member controlling the application of power to the motor, a pneumatically movable member operatively attached to the contact member and normally constrained in central position, a source of pneumatic pressure, branch passages of substantially equal capacity leading the pneumatic pressure to the opposite sides of the pneumatically movable member, valve means for differentially venting the branch passages, differential means actuated by relative movement of the primary movable member and the driven member to position the valve means, two closed chamber

members each having a rotative vane pivoted therein and forming a partition, and conduits connecting the corresponding internal sides of the two chamber members, one vane being operatively connected to the manual controller and the other vane being operatively connected to the contact member.

8. In gunnery, sight controlling mechanism comprising a rotatable mount, a sight on the mount, training means for the mount, a manual controller, two variable speed drives each including a rate control member and an output member, means operatively connecting the manual controller to the rate control member of one variable speed drive, means operatively connecting the output member of the said one variable speed drive to the rate control member of the other variable speed drive, a servo motor connected to operate the training means, a pneumatic control for the servo motor comprising a movable contact member controlling the application of power to the motor, a pneumatically movable member operatively attached to the contact member and normally constrained in central position, a source of pneumatic pressure, branch passages of substantially equal capacity leading the pneumatic pressure to the opposite sides of the pneumatically movable member, valve means for differentially venting the branch passages, and means for differentially connecting the manual controller and the output member of said other variable speed drive to actuate the valve means.

9. In gunnery, sight controlling mechanism comprising a rotatable mount, a sight on the mount, training means for the mount, a manual controller, two variable speed drives each including a rate control member and an output member, means operatively connecting the manual controller to the rate control member of one variable speed drive, means operatively connecting the output member of the said one variable speed drive to the rate control member of the other variable speed drive, a servo motor connected to operate the training means, a pneumatic control for the servo motor comprising a movable contact member controlling the application of power to the motor, a pneumatically movable member operatively attached to the contact member and normally constrained in central position, a source of pneumatic pressure, branch passages of substantially equal capacity leading the pneumatic pressure to the opposite sides of the pneumatically movable member, valve means for differentially venting the branch passages, means for differentially connecting the manual controller and the output member of the said other variable speed drive to actuate the valve means, two closed chamber members each having a rotative vane pivoted therein and forming a partition, and conduits connecting the corresponding internal sides of the two chamber members, one vane being operatively connected to the manual controller and the other vane being operatively connected to the contact member.

10. In a follow-up system including a primary movable member, a servo motor and a driven member operated by the servo motor, a variable speed device having an output member for driving the primary movable member, a manual controller for regulating the speed of the variable speed device, a controller for the servo motor, means differentially connecting the manual controller and the output member of the variable speed device to actuate the controller for the

servo motor, and impulse transmitting means connected to be actuated by the manual controller and operative upon the controller of the servo motor to give an initial impulse to the controller for the servo motor upon movement of the manual controller.

11. In a follow-up system including a primary movable member, a servo motor and a driven member operated by the servo motor, a variable speed device having an output member for driving the primary movable member, a manual controller for regulating the speed of the variable speed device, a controller for the servo motor, means differentially connecting the manual controller and the output member of the variable speed device to actuate the controller for the servo motor, and yieldable motion transmitting means connected to be actuated by the manual controller and operative upon the controller of the servo motor to apply a bias thereto tending to actuate said servo motor controller upon movement of the manual controller.
